UNITED STATES PATENT OFFICE.

WILLIAM C. CALKINS, OF MOMENCE, ILLINOIS.

ELECTRICAL SWITCH.

SPECIFICATION forming part of Letters Patent No. 687,422, dated November 26, 1901.

Application filed February 23, 1901. Serial No. 42,555. (No model.)

To all whom it may concern:

Be it known that I, WILLIAM C. CALKINS, a citizen of the United States, residing at Momence, in the county of Kankakee and State 5 of Illinois, have invented certain new and useful Improvements in Electrical Switches; and I do hereby declare the following to be a full, clear, and exact description of the invention, such as will enable others skilled in 10 the art to which it appertains to make and use the same.

My invention relates to certain improvements in electrical switches more especially designed for use in connection with dynamos.

15 It has for its object principally to transfer the current or "load" from either a number of dynamos or from dynamos conjointly, and to effect such transfer without interruption of the current, and to generally improve the 20 switch mechanism.

It consists of the novel combination and arrangement of the constituent parts of the switch, substantially as hereinafter more fully disclosed, and specifically pointed out by the 25 claims.

In the accompanying drawings illustrating the preferred embodiment of my invention, Figure 1 is a front elevation. Fig. 2 is a rear elevation. Fig. 3 is a horizontal section.

30 Latitude is allowed herein as to details, as they may be changed or varied at will without departing from the spirit of my invention and the same yet remain intact and be protected.

35 In constructing and practicing my invention I provide a suitable base 1 of some non-conducting material—as slate, marble, &c.—and preferably support it at the corners upon short posts or studs 2, by preference comprising screw-bolts 2^a, passed through said base, and a board or bracket 2^b, itself adapted to be suitably secured in position. The screw-bolts 2^a have slipped thereon, between said base and board, sleeves or stops 2^c to provide 40 for spacing off said base to make room for the reception of certain parts arranged upon the rear side of said base.

A plurality or number of metallic bars or conductors 3 have one end of each pivoted 50 to a lug 3^a, secured to the base 1, and the opposite end of each pivotally connected to a bar 3^b, preferably of some non-conducting

fibrous material, and this last-named bar has fixed to it about centrally a handle 3^c, the whole having the function of a series of levers, the purpose of which will be presently disclosed. A suitable strip or bar 3^d of fibrous or non-conducting material may be secured to the base 1 directly in rear of the conductors 3, adapted to effect a close contact or engagement between said conductors and the keepers or contact-points. A number of lug-sections or "bridges" 4 are also secured to the base 1, opposite the lugs 3^a, alined lugs and lug-sections having a "cut-out" or fusible connection 4^a. Said connection consists of a fusible wire or "fuse" with its ends preferably soldered to the bent or upturned ends of small pieces or terminals 4^b, detachably connected or screwed to each alined 7c lug-section or bridge and lug, respectively. The lug-sections or bridges 4 are adapted to have interposed or inserted between each two a metal plug or circuit maker and breaker 5 to provide for cutting out the current when 75 desired, while each of the outer or upper sections has a terminal or screw-threaded extension 5^a passed through the base 1 and projecting therefrom, and to said terminals are connected the line-wires. To the base 80 1 are also secured contact-points or keepers 6^a, four for each two or pair of lever bars or conductors 3, of U shape, with the normally top end of the U of each two contact-points or keepers for each conductor or 85 lever-bar facing each other for the reception of such conductor in either direction of movement. Also one contact-point or keeper 6 of each pair or two is relatively elongated, one of each two pairs having its preferably screw-threaded extension or terminal 6^b, which passes through and is nutted to the base 1, connected up, as at 6^c, with each of two dynamos. The companion contact-points or keepers 6^a of each of two pairs are connected 90 up with the diagonally opposite two terminals of lug-sections or bridges 4 by insulated wires or connections 6^d. The contact-points or keepers 6^a of the other two pairs have their similar screw-threaded extensions or terminals 6^b also in like manner passing through and secured to said base, connected up also with diagonal terminals of other of the bridges or lug-sections 4 by insulated wires 100

or connections 6'. The aforesaid arrangement of parts provides for effecting connection between these contact-points or keepers, the line-wires, and the dynamos and for taking or transferring the current or load from either of the dynamos or conjointly from the two dynamos to the line-wires, and yet effect the same without interruption of the current.

In operation it will be seen that with the series of conductors 3 standing perfectly vertically, when they will all be in engagement with elongated contact-points or keepers 6, both dynamos are utilized. By grasping and actuating the handle 3^c, so as to shift or move the conductors 3 either to the right or left, one or the other of the dynamos may be brought into use, as may be necessary.

The fusible cut-outs may be omitted or used, as desired.

Having thus fully described my invention, what I claim, and desire to secure by Letters Patent, is—

1. An electrical switch comprising a number of pairs of pivoted conductors and contact-points, each of U shape with their open ends facing each other and adapted to receive said conductors, arranged in an electric circuit, and means for conjointly actuating said conductors and engaging them alternately with said contact-points or keepers, substantially as set forth.

2. An electrical switch comprising a number of pairs of pivoted conductors and contact-points, connected up in electric circuit, and such contact-points or keepers being of U shape, with their open ends facing each other and adapted to receive said conductors, means for effecting the conjoint actuation of said conductors, said conductors being connected to a common bar having a handle, substantially as set forth.

3. An electrical switch comprising a number of pairs of pivoted conductors and contact-points connected up in electric circuit, said contact-points being U shape, with their open ends presented toward said conductors, and said conductors being connected to a common hand-actuated bar, substantially as set forth.

4. An electrical switch comprising a number of pairs of pivoted conductors and contact-points or keepers connected up in electric circuit, and such contact-points or keepers being of U shape, with their open ends facing each other and adapted to receive said conductors, said contact-points or keepers being arranged in pairs, one pair for each conductor, and a certain contact-point of each of two pairs being connected to one source of electrical supply and a certain contact-point of each of the remaining two pairs being connected to a separate source of supply, means to effect the conjoint actuation of said conductors, substantially as set forth.

5. An electrical switch comprising a number of pairs of pivoted conductors, corresponding "bridges" or lug-sections connected to

line-wires, and to said conductors, pairs of contact-points or keepers, one pair for each conductor and a certain contact-point or keeper of each of two pairs connected to one source of electrical supply and a certain contact-point of each of the remaining two pairs being connected to a separate source of supply, means for connecting the other or companion contact-points or keepers with terminals of said "bridges" or lug-sections, and means for conjointly actuating said conductors, substantially as set forth.

6. An electrical switch, comprising pairs of pivoted conductors adapted for conjoint actuation, corresponding "bridges" or lug-sections connected to line-wires and said conductors, pairs of contact-points or keepers, one of each pair being relatively elongated and the elongated contact-points being connected in pairs or twos to electrical sources of supply, respectively, and means of connection between said "bridges" and the other or companion contact-points, substantially as set forth.

7. An electrical switch comprising pairs of electrical conductors adapted for conjoint operation, corresponding "bridges" or lug-sections having connection with the line-wires and fusible connections with said conductors, pairs of U-shaped contact-points or keepers, one of each pair being elongated and the elongated contact-points being connected in pairs to electrical sources of supply, respectively, and means of connection between the other or companion contact-points and said lug-sections, substantially as set forth.

8. An electrical switch comprising pairs of pivoted conductors, corresponding "bridges" or lug-sections, having line-wire connections, plugs adapted to engage or connect said lug-sections, fusible connections between said "bridges" and conductors, pairs of contact-points or keepers, one of each pair being elongated and the elongated contact-points being connected in pairs to electrical sources of supply, respectively, and means connecting the other or companion contact-points or keepers to said "bridges" or lug-sections, substantially as set forth.

9. An electrical switch comprising pairs of pivoted conductors, means for conjointly actuating said conductors, corresponding "bridges" or lug-sections having terminals adapted to be connected to the line-wires, pairs of contact-points or keepers of U shape with the open ends of each pair facing each other, one of each pair being relatively elongated, the elongated contact-points or keepers being connected up in pairs to electrical sources of supply, respectively, and wire connections between said "bridges" or lug-sections and the other or companion contact-points or keepers, substantially as set forth.

10. An electrical switch comprising pairs of pivoted conductors, means for conjointly actuating said conductors, corresponding "bridges" or lug-sections having terminals

adapted to be connected to the line-wires, pairs of U-shaped contact-points or keepers with the open ends of each pair facing each other, and adapted to provide for conjoint 5 or simultaneous engagement with said conductors, respectively, to prevent the interruption of the current as said conductors are moved from one contact-point or keeper to the other in transferring or taking the "load" 10 or current from either of a number of elec-

trical sources of supply, and means of connection between said "bridges" or lug-sections and a contact-point or keeper of each pair, substantially as described.

In testimony whereof I affix my signature 15 in presence of two witnesses.

WILLIAM C. CALKINS.
